UNITED STATES PATENT OFFICE.

WALTHER WEGMAN-BOSSERT, OF ZURICH, SWITZERLAND, ASSIGNOR TO
EMIL WUHRMANN-LAUFFER, OF SAME PLACE.

BOOT OR SHOE.

SPECIFICATION forming part of Letters Patent No. 668,364, dated February 19, 1901.

Application filed January 31, 1900. Serial No. 3,549. (No model.)

To all whom it may concern:

Be it known that I, WALTHER WEGMAN-BOSSERT, a citizen of Switzerland, and a resident of Zurich, Switzerland, have invented 5 certain new and useful Improvements in Boots or Shoes, of which the following is a specification.

The object of my present invention is to provide an improved closing device for boots and shoes, said device being adapted to be 10 easily and readily operated, as hereinafter fully described and claimed, reference being made to the accompanying drawings, wherein—

15 Figure 1 is a side elevation of a lady's boot equipped with the improved closing device. Fig. 2 is a plan view of another boot. Fig. 3 is a plan view of the closing device having four spiral springs. Fig. 4 is a side elevation. 20 Fig. 5 shows a plan view of a closing device having two spiral springs. Fig. 6 is a side elevation.

The improved closing device is composed of spiral springs *b*, and I preferably employ 25 two or four spiral springs, arranged substantially parallel with each other and secured at one end to a small cross-piece *a*, the ends *a*² of which are turned downwardly at right angles for the purpose of securing the same to 30 the uppers of boots and shoes. Washers *g*, suitably secured to said downwardly-turned

ends *a*², provide a perfect fastening of the latter to the leather. The opposite ends of said spiral springs are secured to a link *a'*, to which is pivotally attached a double eye *d c*, the 35 part *d* of which is hinged to the part *c* and serves as a handle, while the part *c*, hinged to the cross-piece *a*, engages the hook *e*, suitably secured on the opposite edge of the shoe or boot. An ornamental plate *f* may be slipped 40 over the spiral springs, as shown in the drawings. A slight pull on the eye *d* serves to engage the eye *c* with the hook *e* or to disengage the same from the latter.

Having fully described my invention, what 45 I claim, and desire to secure by Letters Patent, is—

A closing device for boots and shoes, comprising a plurality of spiral springs, a cross-piece to which the ends of said springs are 50 attached, said cross-piece adapted to be secured to the uppers of the shoe, a double eye attached to the other ends of the spiral springs and adapted to engage a hook secured on the opposite side of the uppers, said double eye 55 provided with a pivoted part serving as a handle, substantially as set forth.

WALTH. WEGMAN-BOSSERT.
